FIG-7

UNITED STATES PATENT OFFICE.

FRANK A. NIEBERDING, OF CLEVELAND, OHIO; MARGARET H. NIEBERDING ADMINISTRATRIX OF SAID FRANK A. NIEBERDING, DECEASED.

GAS BURNER.

Application filed January 30, 1922. Serial No. 532,551.

To all whom it may concern:

Be it known that I, FRANK A. NIEBERDING, a citizen of the United States, residing at Cleveland, in the county of Cuyahoga and 5 State of Ohio, have invented a certain new and useful Improvement in Gas Burners, of which the following is a full, clear, and exact description, reference being had to the accompanying drawings.

10 This invention relates generally to the class of gas stoves or heaters, and has to do more particularly with an improved burner for use in stoves or heaters of this character, this application being in part a division of 15 my former application Serial No. 490,574, filed August 8, 1921.

Among the several objects of the invention are the provision of a burner through which a uniform distribution of gas to all 20 jet openings is effectually accomplished; to provide a unique tip for the jet openings which, while affording the maximum flow of gas, causes the gas to issue quietly from the openings under all adjustments of the 25 valve; to so design the tip with respect to the jet opening as to avoid the necessity of a gas-tight joint between the tip and sides of the opening inasmuch as any gas escaping between the periphery of the tip and 30 the sides of the opening will be entrained in the column of gas issuing through the tip and burn therewith without impairing the character of the flame; and to provide a burner wherein, notwithstanding the 35 free emission of the gas through the jet openings, propagation or "back-firing" is effectually avoided.

With these objects in view, and others hereinafter appearing, the invention may 40 be defined as consisting of the combination and arrangement of parts set out in the claims annexed hereto and illustrated in the drawings accompanying and forming a part hereof and wherein Fig. 1 is a central vertical section from front to rear through a heater incorporating my improved burner; Fig. 2 is a fragmentary horizontal section through the heater, on a scale somewhat enlarged over that of the former view, the 45 section being taken at about the plane of the burner; Fig. 3 shows the burner and adjacent stove parts in sectional front elevation; Fig. 4 is a section on the line 4—4 of Fig. 2 and on a further enlarged scale; Fig. 5 is a fragmentary perspective view, much

exaggerated as to size, of my present preferred form of burner tip; and Figs. 6, 7 and 8 show modifications of the tip.

The heater casing comprises, generally, a front frame 1, side walls 2, and a back wall 3 (preferably of suitable refractory material) which extends between the rear edges of the side walls 2 and is supported upon a cross member 4 that is carried by and between the side walls and is connected thereto where said walls join the legs 5 that support the rear portion of the casing. A flue connection 6 is carried by a top wall 7, and into the large opening of the front frame of the casing fits a reflector 8, while a fender 9 is applied to the front frame below said opening.

Burner supporting ledges 10 are carried by the side walls 2 below the bottom of reflector 8, and in the present instance these 75 ledges consist of angle bars which have vertical flanges 11 that are secured in any suitable manner to the side walls 2 (see Figs. 1, 2 and 3).

The burner is composed of top and bottom shells 15 and 16, respectively, and these shells meet in a horizontal plane with a broken joint at 17 which may be calked or sealed with a suitable substance and drawn tightly together by bolts 18 which are engaged through ears 19 and 20 of the respective shells. Wings 21 extend from the ends of the bottom shell 16 and rest upon the ledges 10 to which they may be secured, as by bolts 22. The top shell is provided 80 throughout its length with gas emitting openings 23 (hereinafter referred to as jet openings or orifices), the shell being flanged about the individual openings to provide bosses within the upper ends of which tips 24 may be inserted. These tips will be described in detail hereinafter. Shoulders 25 are formed on the interior of the shell 16 in the region of the joint 17, and a distributor 26 is held between the shoulder 95 90 and the top wall of shell 15. This distributor is in the form of a transversely curved plate and has projections 27 which are adapted to engage the top wall of the shell 15 thereby to hold the edges of the plate against dislodgment from the shoulders 25. As will be seen more clearly from Fig. 2, the distributor is provided near its ends with slots 28 and near its center with slots 29. The former slots enlarge 100 105 110

ally inwardly from their outer ends, while the latter slots decrease in area quite abruptly from their outer toward their inner ends. It will be observed that while the 5 top shell 15 is substantially uniform in cross section throughout its length, the bottom wall of the lower shell is gradually inclined downwardly from its outer end toward its middle portion where it is provided with 10 an opening 30 through which the interior of the burner communicates with a mixing tube 31, the tube and shell having mating parts which are shown as fitted together with a broken joint, as indicated at 32, and 15 which joint may be calked with a suitable sealing substance and thus rendered leak-proof when the shell and mixing tube are drawn together by bolts 33 which are engaged through ears 34 and 35 of the respective parts.

Attention is called particularly to the shape of the mixing tube. It will be observed from Figs. 1, 2 and 4 that the same extends rearwardly and downwardly from the 25 burner and is then turned forwardly in a gradual curve where it terminates in a flared end that is substantially flush with the front of the casing. From Figs. 2 and 3 it will be seen that the tube is enlarged in a 30 lateral direction as it approaches the burner so that its capacity gradually increases inwardly from a point adjacent its flared outer end. It is quite generally known that this latter condition is essential to a proper 35 mixing of the gas with the air, and it is also a recognized fact that the mixing tube must be of sufficient length to allow the gas and air to properly intermingle before they enter the burner. By constructing and arranging the tube as I do I maintain the 40 proper length, provide a symmetrical design, and insure convenience in making connection between the valve (situated at the forward end of the mixing tube) and the gas supply pipe which, in the case of the so-called fireplace heater, comes up through the floor under and well toward the rear of the heater, such connection being illustrated in Fig. 1 and further commented upon hereinafter. This arrangement, therefore, eliminates a very common difficulty and annoyance that is experienced in the installation 45 of the heaters, especially of the fireplace type. Furthermore, the goose neck formation of the mixing tube effects a foreshortening which results in the valve being situated close up to the front of the heater and permits of the use of a comparatively shallow fender.

As gas enters a burner, its natural tendency is to continue in the same direction in which it is traveling when admitted through the mixing tube. In the present instance this would result in a greater amount of gas 50 coming from the jet orifices near the center

of the burner than would pass through the ones toward the ends, were it not for the distributor 26 which, by virtue of its restricted openings 29, deflects a part of the gas laterally toward the ends of the burner, only a 55 limited amount of the gas passing through said openings. When the gas is deflected laterally, the tendency is for it to rush to the ends of the burner where its upward passage is retarded by the somewhat restricted 60 outer ends of the openings 28. Consequently, by reason of the shapes of these and the former openings, a very uniform distribution of gas from one end to the other is accomplished, and all jet orifices receive a substantially like amount of gas.

A suitable gas valve 38 is shown as maintained in proper relation to the receiving end of the mixing tube by means of a yoke 39 which is preferably cast integral with the 65 tube, the valve being thus positioned for a convenient attachment, as through a union 40, with the forward extension 41 of the supply pipe 42, these parts being shown in Fig. 1 as they would appear particularly in 70 a fireplace installation. The valve stem 43 projects forwardly and is equipped with the usual handle 44.

Associated with the jet openings or orifices of the burner are lugs 45 which serve to support in proper relation to said openings, radiants 50 (shown in dot and dash lines in Fig. 1) that rest against the back wall and are restrained at their upper ends from accidental tilting forwardly by a bar 51 that is carried, through arms 52, from the top wall 7, the arms being shown in the present embodiment as secured to the top wall through certain of the bolts 53 which attach the 80 flange of the flue connection 6 to said wall.

Returning now to a detailed description of the present preferred form of tip, shown in perspective in Fig. 5, the same comprises a frame 65, preferably of sheet metal, that fits reasonably snugly within a jet opening and has, on its upper edge at its four corners, outwardly and downwardly extending lugs 66 which fit over the corners of the boss that surrounds the jet opening. A suitable grouting material or cement may, if desired, be filled in about the tip to seal the joint between it and the boss. However, in this form of the tip, as in the forms illustrated in Figs. 7 and 8, it is not regarded as important that the joint between the tip and boss be sealed or packed because any gas escaping about the sides of the tip would naturally flow into the column of gas issuing through the tip and would not in any way impair the character of the flame. A series of crimped or corrugated strips 67 are forced into the frame 65, their upper edges being substantially flush with the top of the frame while the end portions of their lower edges engage an inwardly directed flange 68

that surrounds the lower side of the frame. According to the present design, the corrugations of the strips 67 give a honey comb appearance to the tip. The strips, being thin, have very little retarding effect on the flow of gas, but they are made wide enough to afford sufficient depth to the individual orifices as compared to the latter's cross sectional area to effectually prevent the flame from back-firing into the mixer.

Fig. 6 shows a form of tip identical with that above described except that instead of having ears 66 at its corners, it has an outwardly and downwardly extending peripheral flange 70 which engages over the top edge of the boss and imparts to the structure a neat and attractive appearance. However, in this form of tip, it is necessary to thoroughly seal the joint between it and the wall of the aperture for otherwise the gas escaping about the tip and passing out under the flange 70 would be so far removed from the column of gas issuing through the tip that it would burn separately therefrom. Obviously, such a result would be quite undesirable for the escaping gas would frequently, if not always, burn beyond the radiants 50, while the normal and desirable action is for all gas issuing from the jet openings to rise inside and burn within the hollow fret-work radiants.

Figs. 7 and 8 show modifications of the tip which will be readily understood from the illustrations; and in these, as in the cases just described, the tips are preferably made of sheet metal.

Having thus described my invention, what I claim is:

1. A burner of the class set forth comprising elongated top and bottom shells, means for drawing said shells together with a leak-proof joint, a mixing tube carried by the lower shell, the top shell having a series of jet openings, and means within the burner and retained in place by cooperation with the top and bottom shells for uniformly distributing the gas from the mixing tube to all jet openings.

2. A burner of the class set forth comprising elongated top and bottom shells, the former having a series of jet apertures spaced apart throughout its length, a distributor comprising a plate situated within the burner and extending substantially from end to end thereof, said plate being provided adjacent its ends with openings enlarging inwardly from the ends of the burner, and openings adjacent its middle portion which decrease in area toward the center of the burner, and a mixing tube opening into the lower shell adjacent the middle portion thereof.

3. A burner of the class set forth comprising a hollow elongated body having a series of jet apertures along its top, a mix-

ing tube opening into the bottom of said body, and a deflector comprising a plate situated within said body and extending substantially from end to end thereof, said plate being provided adjacent its ends with openings increasing in area inwardly from the ends of the body, and openings adjacent its middle portion decreasing in area towards the center of the body.

4. A burner of the class set forth comprising a hollow elongated body portion having a series of jet apertures spaced apart throughout its length and a mixing tube opening into said body portion at about the longitudinal center thereof, said tube extending downwardly and rearwardly from said body portion and then forwardly beneath the same, the tube enlarging gradually inwardly from its forward end to where it joins the burner, and a deflector situated within and extending longitudinally of the burner and having openings of such shape as to effect a substantially uniform distribution of gas from the mixing tube to all jet apertures of the burner.

5. A burner of the class set forth comprising elongated top and bottom shells, the former having a series of jet apertures, radiant supporting and positioning lugs adjacent each aperture, the lower shell having an opening at its longitudinal center, a mixing tube secured to the lower shell in register with said opening, and a deflector within the burner and extending longitudinally thereof and designed to effect a uniform distribution of gas from the mixing tube to all jet apertures.

6. A burner of the class set forth comprising top and bottom shells, the former having a series of jet apertures and the latter an opening at its longitudinal center, means for securing the shells together with a leakproof joint, and a mixing tube likewise secured to the bottom shell in register with the opening thereof, the bottom shell having supporting wings extending from the ends thereof.

7. A burner of the class described comprising an elongated casing having a series of jet openings, and a mixing tube extending at substantially right angles with respect to the longitudinal axis of the casing rearwardly therefrom and thence downwardly and forwardly beneath the same, a fuel control valve, and means supporting said valve forwardly of and in proper relation to the mixing tube.

8. A tip for burners of the class set forth comprising a frame having an inwardly directed flange at its lower end and an outwardly and downwardly flaring skirt at its upper end, and a plurality of corrugated strips extending across the frame and cooperating to provide a series of individual jet apertures.

9. A tip for burners of the class set forth comprising a frame having outwardly extending supporting lugs at its upper edge, and a plurality of corrugated strips extending across the frame and contacting with each other to produce a series of individual jet apertures.

10. A burner of the class described comprising an elongated hollow body having a series of jet openings, a mixing tube extend-

ing downwardly and forwardly therefrom, a fuel control valve, means supporting said valve forwardly of and in proper relation to the mixing tube, and radiant positioning lugs carried by the body adjacent the jet openings.

In testimony whereof, I hereunto affix my signature.

FRANK A. NIEBERDING.
